UNITED STATES PATENT OFFICE

PAUL ERICH BRUNO SANDER, OF CHEMNITZ, GERMANY, ASSIGNOR TO CHEMNITZER STRICKMASCHINENFABRIK A. G., OF CHEMNITZ, GERMANY, A CORPORATION OF GERMANY

CIRCULAR KNITTING MACHINE

Application filed July 16, 1929, Serial No. 378,597, and in Germany July 18, 1928.

In my German Patent No. 484,191, issued on October 10, 1929, I disclosed an invention relating to the production of fancy goods in which the needle pushers or jacks which lie in recesses in the indentations of the needle bed, or the needles themselves are carried by a conveyor device such as a guide rail out of these recesses to a pattern apparatus which forces back the jacks or the needles which are not to operate into their recesses and withdraws them from the range of action of the cam surface in the cam cylinder. The jacks or needles not acted upon by the pattern apparatus are guided up over, say a cam and return over a second cam surface, or similar guiding device, to their initial position. All the jacks or needles now lie in the indentation of the needle bed until they are carried by a succeeding guiding device to a pattern apparatus.

According to the present invention, the jacks or needles not acted upon by the pattern apparatus, after passing the two guiding devices, cams say, over which they pass, are not again brought back into the initial position by means of a second cam but the jacks or needles, after their sorting by the pattern apparatus into two groups and after each passage, say, a needle actuating cam, are re-grouped by positioning devices provided one for each group so that at the next cam the jacks or needles are actuated which were not actuated in the preceding series of operations, and vice versa.

Instead of carrying, as with known circular knitting machines, the separate jacks or needles by means of a special guiding device from their initial positions to each pattern apparatus, and after their passage over or through the needle actuating means of bringing them all back into the initial position by means of a second guiding device, according to the invention the jacks or needles not acted on by the pattern apparatus as in my German Patent No. 484,191, after passing over or through the actuating means may remain in position and the jacks or needles forced back by the pattern apparatus into the initial position can be brought forward by a positioning device.

In order that the needles which pass through or over the actuating means, may not slide back after actuation into the deeper indentations of the needle cylinder and thus be displaced from their working position, according to the invention a further special guiding device is provided retaining the jacks or needles passing through the actuating means, in their forward position. All the jacks or needles are then, in the forward position, carried to the succeeding pattern apparatus.

The separate pattern apparatus provided with the known circular knitting machine may also, according to the invention, be entirely dispensed with as the jacks or needles inserted in any desired manner by hand are brought by the positioning device in groups alternately in and out of engagement with the successive actuating means.

In the drawings actuating means with positioning devices constructed according to the invention are shown as examples:—

Figure 1 shows the arrangement of a cam guide provided behind the pattern apparatus for the jacks or needles sorted into two groups, as an example, in perspective.

Figure 2 shows another arrangement of the cam guide.

Figure 3 shows two of the cam surfaces disposed in succession around the needle bed with the jacks in their range, in perspective, and

Figure 4 shows the parts shown in Figure 3 in horizontal section.

With the circular knitting machines with cams as shown in Figure 1, 1 is a cam surface provided behind a pattern apparatus. The jacks have been sorted into two groups by the pattern apparatus, not shown in the drawings, one group of the jacks 2 being forced back by the pattern apparatus into the indentations of the needle cylinder, so that they do not pass over the cam 1, while the group of jacks 2¹ is not influenced by the pattern apparatus, so that they remain in the advanced position and pass over the cam surface 1. Positioning devices 3, 4 are now provided in the path of both jack groups which put the two groups alternately into the working or stationary position. The

10 jacks 2 which do not pass over the cam 1 are guided by the positioning boss 3 shaped as shown, into the working position, that is, into the advanced position, so that they pass up the succeeding cam. The jacks 2¹ which have passed over the cam 1 are brought into the normal inoperative position shortly before leaving the cam, by the positioning boss 4, that is, to say, they are forced back into the indentations of the needle cylinder, so that they cannot pass over the succeeding following cam. This process is repeated mutatis mutandis in front of each succeeding cam.

15 With an arrangement of the positioning devices shown in Figure 2, 1 is a cam arranged behind the pattern apparatus. The jacks 2 forced back by the pattern apparatus into the normal position, that is, into the 20 needle bed indentations, do not pass over the cam, as the heels 2a do not stand out far enough. The cam is only passed over by the jacks 2¹ which have not been forced back into the normal inoperative position by the 25 pattern apparatus, so that their heels 2a extend far enough forward to pass up the cam 1. The jacks 2 of which the heels do not pass over the cam 1 are caused to move forward by the positioning boss 3 from their 30 normal inoperative position. The positioning boss 3 is so arranged that viewed in the direction of rotation of the jacks it is slightly outwardly inclined, so that the jacks 2, the recesses 5 on the heels 2a of which engage the boss are forced outwards.

In order that the jacks 2¹, which pass over the cam 1, may all take up the same position as the needle feelers 2 brought forward out of the normal inoperative position by the action of the position boss 3, a further second positioning boss 4 is provided at the end of the cam surface which prevents the jacks on the downward movement sliding into the deeper indentations of the needle cylinder, and thus getting out of the working position. In the forward position all the jacks are then carried to a further pattern apparatus.

With the form of construction of the circular knitting machine according to Figures 3 and 4, the jacks A are carried inwards, on the cam I shown in the drawings, by the positioning boss 6 so that they do not pass over the succeeding cam II. The jacks B, which do not pass over the cam I, are carried outwards by the positioning boss 7 so that they pass over the cam II. In the cam II the needles B are moved inwards by the positioning boss 8, while the needles A not operated by the cam II, are again carried outwards by the positioning boss 9.

The sorting of the needles may take place in any desired manner, as for example by hand.

What I claim and desire to secure by Letters Patent of the United States is:—

1. A needle cylinder for a circular knitting machine, having, with successive cams, a plain groove for jacks and successive cam grooves for jacks, each of said cam grooves including an upward incline from the plain groove and a downward incline thereto, means in the plain groove below each of the cams for moving the jacks which pass in such groove, laterally outwardly therein into a position in which they will engage the upward incline of the next succeeding cam groove, and means on the downward incline of each cam groove for moving the jacks which pass in such groove, laterally inwardly therein into a position in which they will escape engagement with the upward incline of the next succeeding cam groove. 75

2. A needle cylinder for a circular knitting machine, having, with successive cams, a plain groove for receiving the heel parts of jacks and successive cam grooves for receiving the heel parts of jacks, each of said cam grooves including an upward incline 85 from the plain groove and a downward incline thereto, an elongated boss member in the plain groove below each of the cams for engaging jack heels and switching them laterally outwardly into a position in which 90 they will engage the upward incline of the next succeeding cam groove, and an elongated boss member on the downward incline of each cam groove for engaging the jack heels and switching them laterally inwardly 100 into a position in which they will escape engagement with the upward incline of the next succeeding cam groove.

3. A needle cylinder for a circular knitting machine, having, with successive cams, 105 a plain groove for jacks and successive cam grooves for jacks, each of said cam grooves including an upward incline from the plain groove and a downward incline thereto, means in cooperation with the jacks for 110 intervally switching the same, said means consisting of heels on the jacks for engaging the grooves and notches, and elongated bosses in the grooves for engaging notches, certain of said bosses being in the plain groove 115 and arranged in an oblique outwardly extending direction therein to switch the heels outwardly into a position for engagement with the next succeeding upward incline, and certain of said bosses being in the cam 120 grooves and arranged in an oblique inwardly extending direction therein to switch the heels inwardly into a position for escaping upward incline. 125

PAUL ERICH BRUNO SANDER.
